DESIGN FOR A LAMP BASE

Jordan A. Post, Detroit, Mich.

Application May 3, 1946, Serial No. 129,239

Term of patent 3½ years

(Cl. D48—20)

To all whom it may concern:

Be it known that I, Jordan A. Post, a citizen of the United States, residing at Detroit, in the county of Wayne and State of Michigan, have invented a new, original, and ornamental Design for a Lamp Base, of which the following is a specification, reference being had to the accompanying drawing, forming part thereof.

Fig. 1 is a side elevational view of a lamp base showing my new design; and

Fig. 2 is a sectional view taken on line 2—2 of Fig. 1.

I claim:

The ornamental design for a lamp base, as shown.

JORDAN A. POST.
